UNITED STATES PATENT OFFICE.

WILLIAM OLIVER KEELING, OF GAINESVILLE, FLORIDA.

CARBURETOR.

Application filed September 28, 1925. Serial No. 59,112.

This invention relates to a carburetor adapted to make high grade illuminating gas from low test gasoline.

An object of the invention resides in providing a carbureting apparatus adapted to produce the standard grade of illuminating gas from low grade gasoline and cold air so that small gas making plants may be constructed and used in houses or small shops 10 in conjunction with the standard gas consuming apparatus manufactured for using the standard gas as produced in large cities.

A further object of the invention resides in providing a structure of the above mentioned character, which will produce standard test gas operating on the principle of absorption in which air forms the absorbing agent for the gasoline.

Another object of the invention resides in providing an apparatus including a combined absorption chamber and dehydrater in which the structure for producing the absorption of the gasoline by the air and the dehydration thereof to produce a dry gas 25 of standard test are of specially constructed character to permit the ready assemblage of the parts.

The invention also comprehends other objects and improvements in the details of 30 construction and arrangement of parts which are more particularly pointed out in the following detailed description and in the claims directed to a preferred form of the invention, it being understood however that 35 various changes may be made in the size, shape, construction and arrangement of the parts without departing from the spirit or scope of the invention as herein set forth.

In the drawings forming part of this application,

Fig. 1 is a side elevation of the interconnected apparatus forming a carbureting and storing machine which is shown enclosed within a suitable housing shown in section.

Fig. 2 is a vertical longitudinal sectional view through the absorber and dehydrater.

Fig. 3 is a vertical sectional view on the line 3-3 of Fig. 2.

Fig. 4 is a perspective of one of the trays.

Fig. 5 is an enlarged detail perspective of one portion of one of the trays illustrating particularly the manner of securing the baffle and breaker material in the chambers or 55 pockets of the trays.

It has heretofore been proposed to pro-

duce carbureting devices of the character somewhat similar to the present construction, but which operate on an entirely different principle, namely, that of producing 60 the gas by vaporization or aeration. It has been found, however, from practical experimentation that in order to produce standard test gas comparing with that used in illuminating systems in large cities, it is 65 necessary to use high test gasoline usually of 82 Baumé specific gravity. These known devices will not operate successfully with a low grade of gasoline having a specific gravity of 68 Baumé. The present invention involves the use of the principle of absorption 70 for the production of high test gas from gasoline of low grade such as gasoline having a specific gravity of 68 Baumé.

1 indicates a housing provided in one end 75 with a suitable door or doors indicated by the numeral 2 fitted into said housing and adapted to close the same in such relation as to produce a fire proof container. The carbureting apparatus constructed in accordance with this invention includes a suitable frame work 3 having a plate 4 on the top thereof on which is mounted a suitable electric motor 5 having a belt connection 6 with the pulley thereof and a pulley on a suitable 85 air compressor 7 so that in the operation of the motor the air compressor will be operated in a well known manner for compressing air to be forced through the pipe 8. The motor 5 is supplied with current from a suitable 90 gas operated switch structure which is indicated at 9.

A combined absorption chamber and dehydrater is indicated by the numeral 10 which includes an open top casing 11 on 95 which is secured a suitable cover 12 in air and liquid-tight relation in any suitable manner. This housing 11 is provided with an inlet pipe 13 through which gasoline may be suitably supplied thereto and which is 100 adapted to be filled to the level of the petcock 14, while a petcock 15 is mounted in the bottom of the tank to permit the draining of the housing when desired.

A plurality of trays indicated at 16, 17, 18 105 and 19 respectively and of similar construction, are mounted in inverted relation with in the housing 11 as clearly shown in Figures 2 and 3 for a purpose now to be described. Each of these trays comprises a horizontal wall portion 20, and side walls 21, and one 110 end wall 22. The tray 18 has the end wall

thereof extended substantially beyond the lower edges of the side walls as indicated at 23 in order that when the parts are mounted in the relation shown in Fig. 2, the bottom edge of the wall 23 may be suitably soldered or otherwise secured to the horizontal wall 20 of the tray 16.

Within each of these trays are mounted a plurality of perforated partition walls 24 which are adapted to divide each tray into a plurality of compartments 25 or pockets as they may be termed for the reception of suitable baffle material, indicated generally by the numeral 26. The baffle material used 10 in connection with this invention consists preferably of a plurality of lengths of short rope of a suitable character adapted for positioning vertically within the tray in compact relation as illustrated by the enlarged 15 perspective view in Fig. 5. These rope sections or fragments are secured to the horizontal walls or portions of the trays by being provided with suitable cementitious material as indicated by the numeral 27 on the 20 ends thereof which are inserted into contact with the horizontal wall 20 so that this cementitious material will harden after the insertion of the rope sections into the pockets and effectively retain the same therein.

25 The enclosed ends of each adjacent tray progressing upwardly from the bottom of the housing are positioned in reverse relation with respect to the remaining trays as clearly 30 illustrated by Fig. 2 so as to provide a circuitous and zig-zag upward passage from the bottom of the housing to the top portion thereof. As shown in Figs. 2 and 3, only 35 trays 16, 17 and 18 are provided with the baffle material 26 while the tray 19 is merely 40 provided with partition walls 24 and the pockets thereof remain empty. The trays 16, 17 and 18 form the absorption chamber portion 45 of the device while the tray 19 forms the dehydrating chamber so that all moisture in the mixture absorbed by the air passing through the housing 11 will be separated 50 from the dry gas which is contained within the gas chamber 28 in the top portion of the housing 11. All liquid gasoline separated 55 from the absorption product is returned by gravity to the absorber portion of the housing.

55 The pipe 8 is connected as illustrated in Fig. 2 through the provision of a suitable fitting as indicated at 29 with the chamber 25 at the closed end of the tray 16 so that the compressed air is delivered to the first absorption pocket of the tray 16 from which it passes through the perforated partition 60 wall 24 toward the open end of said tray. Upon leaving the open end of the tray 16 the air is forced upwardly around the end of the tray into the end pocket of the tray 17 and upon passing through the tray 17 moves 65 outwardly around the open end thereof into

the tray 18 and subsequently after passing through the length of the tray 18 and the absorption material in the pockets thereof enters into the dehydrating chamber or tray 19. As the vapor passes through this chamber 70 the liquid portion is separated by the partition wall 24 and is returned to the absorber portion of the housing. The gas from the dehydrator then passes into the chamber 28 and is then in a substantially dry state 75 and which will test up to the standard required for illuminating gas such as is present in use in large cities and is in condition for efficient use with ordinary gas burning apparatus using the usual standard test gas as 80 manufactured for illuminating purposes in large cities.

An outlet pipe 30 is connected with the cover 12 of the chamber to provide a passage for the gas from the chamber 28 to a suitable storage receptacle 31. This receptacle may include a movable dome 32 for containing a variable amount of gas therein under pressure in conjunction with the stationary part 33 in which it is movable and suitably sealed to prevent escape of the gas. Guides 34 may be provided on the side of the stationary part 33 for guiding the movement of the dome 32 relative to said stationary part. Removable dome 32 carries a control member 35 which is movable therewith and projects into proximity of the knife blade of the switch 9 so that the projections 36 thereon are adapted to lie above and below the switch blade for closing the same and opening the same according to the position of movement of the dome 32 so as to automatically maintain a constant supply of gas through the gas supply main 37 which extends and to which may be connected suitable gas burning apparatus.

In the operation of this device the air compressor 7 maintains the supply of gas through the main 37 in accordance with the operation of the dome 32 which controls the pressure of the gas in said outlet main 37. The storage device 34 may be of any desired character as used and well known in the art for the purposes above described.

A suitable controlling device is indicated at 38 for controlling the air supplied to the absorber while a blow-off valve 39 provides for the release of excess pressure in the outlet or air supply pipe generated in the compressor.

In making gas in this apparatus, the air from the compressor enters the housing 11 through the pipe 8 and is conducted below the level of the gasoline therein as indicated at 40 and to the bottom of the housing where it is forced into the tray 16. This air in passing through the trays 16, 17 and 18 is broken up by the packing 26 into minutely divided form so that it will completely and fully absorb the gasoline within the said

trays and the housing. This absorption will gradually take place through the successive breaking up of the air particles in passing through the baffle material and perforated partitions of the trays 16 and 17 and 18 so that as the saturated air leaves the tray 18, it will be fully and thoroughly saturated with gasoline to provide a gas having the proper density and the candle power and upon subsequent passage through the dehydrating tray 19 any excess fuel will be separated therefrom so that when the gas passes into the chamber 28 it will be thoroughly dried, and in condition for use in standard gas burning apparatus. As heretofore set forth this invention produces standard candle power gas efficiently from gasoline having a specific gravity of 68 Baumé.

It will thus be seen from the above description that an efficient carbureting apparatus has been produced which utilizes a combined absorber and dehydrator of simple construction which will efficiently produce absorption of gasoline by air and dehydrate the treated air to produce a dry standard candle power gas.

Having thus described my invention, what I claim as new is:—

1. A device for producing absorption of gasoline by air comprising a closed housing, a plurality of tray members mounted in superimposed inverted position in said housing, said tray members being open at one end and at the top, said tray members being shorter than the housing and having their open ends positioned in staggered relation with the open ends of alternate trays and communicating with the open top of the tray next above adjacent the closed end thereof to provide a continuous circuitous passage from the bottom to the top of said housing, an air inlet communicating with the closed end of the bottom tray, a plurality of rope sections mounted in compact adjacent relation, extending transversely of the passage through said trays and completely filling the trays to form an obstruction in said passage, means securing the ends of the rope sections to the trays, said trays and rope material being normally submerged in liquid fuel whereby air forced through said trays will be broken up into finely divided form to absorb said fuel for producing illuminating gas.

In testimony whereof I affix my signature.

WILLIAM OLIVER KEELING.
